(57) **CLAIM**

The ornamental design for a seashell lock, as shown and described.

DESCRIPTION

FIG. 1 is a front perspective view of a seashell lock in accordance with the invention;

FIG. 2 is a front view of FIG. 1;

FIG. 3 is a back view of FIG. 1;

FIG. 4 is a left view of FIG. 1;

FIG. 5 is a right view of FIG. 1;

FIG. 6 is a top view of FIG. 1;

FIG. 7 is a bottom view of FIG. 1; and,

FIG. 8 is a perspective view thereof, showing the seashell lock in an alternate configuration of use.

The portions of the seashell lock shown in broken lines form no part of the claimed design.
